(57) **CLAIM**

The ornamental design for a single rail flosser tip cartridge, as shown and described.

DESCRIPTION

FIG. 1 is a top isometric view of a single rail flosser tip cartridge showing our new design;

FIG. 2 is a bottom isometric view thereof;

FIG. 3 is a top plan view thereof;

FIG. 4 is a front elevation view thereof, the rear elevation view being a mirror image thereof;

FIG. 5 is a bottom plan view thereof; and,

FIG. 6 is a right side elevation view thereof, the left side elevation view being a mirror image thereof.
